(57) **CLAIM**

The ornamental design for a floor cleaner, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a top left perspective view of a floor cleaner, illustrating our new design;

FIG. 2 is a top right perspective view thereof;

FIG. 3 is a left side view thereof;

FIG. 4 is a right side view thereof;

FIG. 5 is a rear view thereof;

FIG. 6 is a front view thereof;

FIG. 7 is an enlarged top view thereof; and,

FIG. 8 is an enlarged bottom view thereof.

The areas shown in light grey and surrounded by a broken line in the drawings show portions of the floor cleaner which form no part of the claimed design.
